MACHINE FOR FINISHING THE EDGES OF TUBE BLANKS.

No. 469,977.

Patented Mar. 1, 1892.

UNITED STATES PATENT OFFICE.

JOHN B. PERRINS, OF SEYMOUR, CONNECTICUT, ASSIGNOR TO THE SEYMOUR MANUFACTURING COMPANY, OF SAME PLACE.

MACHINE FOR FINISHING THE EDGES OF TUBE-BLANKS.

SPECIFICATION forming part of Letters Patent No. 469,977, dated March 1, 1892.

Application filed August 21, 1891. Serial No. 403,831. (No model.)

To all whom it may concern:

Be it known that I, JOHN B. PERRINS, a citizen of the United States, residing at Seymour, in the county of New Haven and State of Connecticut, have invented certain new and useful Improvements in Machines for Finishing the Edges of Tube-Blanks; and I do hereby declare the following to be a full, clear, and exact description of the invention, such as will enable others skilled in the art to which it appertains to make and use the same.

My invention has for its object to produce a machine simple and inexpensive in construction and rapid and effective in operation for finishing the edges of tube-blanks preparatory to brazing or soldering.

It is of course well understood by those familiar with the art that the brazed tubing of commerce is made by rolling a suitable strip of metal into cylindrical form and then brazing the edges together. As it is found necessary in practice to smooth off and bevel the edges of the blanks before brazing, it has been customary for an operator to finish both edges by hand with a scraper. This operation adds seriously to the cost of production, as considerable time is consumed in finishing the edges of the metal, the expense being greatly increased, furthermore, by the fact that the operation of finishing the edges can only be performed by skilled workmen.

My present machine dispenses entirely with hand labor in finishing the edges of metal and produces very much better results, as both edges are not only finished perfectly smooth, but are left straight and parallel from end to end.

I will now describe my novel machine, referring by numerals to the accompanying drawings, forming part of this specification, in which—

Figure 1 is a plan view; Fig. 2, a side elevation; Fig. 3, an end elevation as seen from the left in Fig. 1; Fig. 4, a perspective of a short piece of tubing with the edges finished ready for brazing, and Fig. 5 is a detail sectional view illustrating the cutter-adjusting mechanism.

It is quite practicable to feed the rolled tube-blanks to the machine either automatically or by hand. As the feeding mechanism

forms no portion of my present invention, I have omitted feeding mechanism and have simply illustrated the operative parts of the machine, it being understood that tube-blanks 55 may be fed to the machine in any suitable or preferred manner.

1 denotes the bed of the machine, which is supported upon suitable legs 2.

3 is the shaft, to which power is applied by 60 a belt (not shown) running over a pulley 4. This shaft is journaled in boxes 5 upon standards 6, extending upward from the bed.

7 is a vertically-movable frame consisting, preferably, of side bars 7^a, with a web 7^b between them. Both ends of the side bars are provided with boxes 8, one end of the frame being supported by shaft 3, which passes through the boxes at that end.

9 is a shaft journaled in the boxes at the 70 other end of the side bars, and 10 is a rotary cutter carried by said shaft. The special form of the cutter is not of the essence of my invention. It is sufficient to say that the cutter is a disk provided on its periphery with 75 suitable cutting-teeth 10^a. Power is applied to this shaft by a belt (not shown) extending from a pulley 11 on shaft 3 to a pulley 12 on shaft 9.

13 is a standard projecting upward from 80 the bed, to which it is rigidly secured by bolts 14. At the upper end of this standard is a curved slot 15.

16 is an enlargement cast upon one of the arms 7^a, and 17 a stud extending outward from 85 this enlargement and passing through slot 15. The outer end of this stud is screw-threaded and is engaged by a lock-nut 18, which is preferably provided with a handle 18^a for convenience in operation. Should it be required at any time to raise or lower the cutter, lock-nut 18 is loosened and the frame raised or lowered, as may be required to place the cutter in the desired position. The parts are then locked in position by tightening up 90 the lock-nut, and do not require to be changed in use unless tubes of another size or unevenness of slot are to be operated upon.

19 denotes a set-screw in enlargement 16, the lower end of which is adapted to engage 100 an enlargement 20 (see Fig. 1) on the inner side of standard 13 and serves as a stop to

limit the downward movement of the frame. This stop is simply a safeguard to avoid the possibility of the cutter dropping down and the teeth being damaged by contact with some portion of the machine should lock-nut 18 become accidentally loosened, and more especially when the lock-nut is not used at all and the frame and cutter are controlled by a foot-lever 21.

22 is a lever, one end of which is pivoted between ears 23 (see Fig. 2, in connection with dotted lines in Fig. 1) on the under side of one of the side bars 7^a.

24 is a rod extending up through the bed of the machine, one end of which is connected to the opposite end of lever 22 and the other to the foot-lever. Lever 22 has its fulcrum on a stud 25 at the upper end of a link 26, the lower end of which is pivoted to a boss 27, extending outward from standard 13. When it is not desired to use the foot-lever, the frame is adjusted in the manner already described to place the cutter in operative position and lock it there. For many classes of work skilled operators prefer not to have the frame locked in position, but subject to the control of the foot-lever. Under such circumstances the lock-nut is not used.

In inserting a tube the operator raises the cutter by means of the foot-lever, and in the same manner retains the cutter in operative position while finishing the edges of a blank, it being of course apparent from Fig. 2 that downward pressure upon the foot-lever will raise the cutter. The engagement of stop 19 with enlargement 20 prevents the possibility of injury to the cutter should it drop down. In order to insure that the frame and cutter shall respond instantly to the movements of the foot-lever, I provide a spring 52, one end of which is connected to the bed, the other to the frame, (see Figs. 1 and 2,) so that when the foot-lever is pressed down the upward movement of the frame and cutter will be against the power of this spring, which will act to draw the frame and cutter downward, the instant pressure upon the foot-lever is relieved.

The tube to be operated upon is passed into the machine in either direction and rests upon supporting-rollers 28, carried by yokes 29 at opposite ends of the machine. The yokes are provided with shanks 30, which extend down through the bed of the machine and are provided near their lower ends with pins 31. These pins engage oblique slots in a slide 33, supported by guides 34 under the bed. The outer end of this slide is given a half-turn and is pivoted to a hand-lever 35 at the end of the machine. It will be seen that oscillation of this lever will act to raise or lower the yokes and rollers 28 simultaneously. The tube while being acted upon by the cutter is held against lateral movement by guide-rollers 36, carried by slides 37, supported by suitable brackets 38, which are cast integral with or rigidly secured to the bed. The special form

of these brackets is of course not essential. In Fig. 3 I have shown the brackets as cast integral and connected at the bottom, shank 70 30 of the yoke at this end of the machine passing through the casting and being supported thereby. The outer ends of slides 37 are bent at right angles to receive adjusting-screws 39, which are threaded to engage the brackets, the angular portion of the slide being held between collars 40, so that rotation of the adjusting-screws will move the slides, and with them the guide-rollers, in or out, as may be required.

41 denotes hand-levers upon the adjusting-screws for convenience in operation.

In order to retain the tube against the slightest oscillatory movement while it is being operated upon, I provide rollers 42, made thin enough to pass between the edges of the blank, and place one of said rollers upon each side of the cutter. These rollers are carried by arms 43^a, extending inward from vertical slides 43, which move in ways on opposite sides of one of the brackets 38, the right bracket being shown in Fig. 3. This right bracket is provided with a vertical slot 44 through it from the front, as seen in Fig. 3, said slot appearing only in dotted lines in said figure, as it is covered by plate 43, and with a vertical slot 45, at right angles thereto, said slot 45 entering from the front, as seen in Fig. 2, and intersecting slot 44.

46 denotes a cross-piece lying in slot 44, the outer ends of which are reduced and screw-threaded to receive nuts 47. These nuts act to clamp slides 43 against the shoulders where the reduced ends of the cross-piece terminate, so that when said cross-piece is moved up or down said slides, and with them rollers 42, are moved up or down also.

48 is a bolt in slot 45, the inner end of which engages the cross-piece, and 49 is a link, one end of which is pivoted on bolt 48 and the other on a bolt 53, which passes through a slot 50 in a hand-lever 51, which is itself pivoted on a bolt 54, engaging the bed. It will be seen that oscillation of the hand-lever will act to raise the link 49 and bolt 48, and with it the cross-piece and slides 43, carrying rollers 42 up or down, as may be required for purposes of adjustment.

It will of course be apparent that the details of construction may be varied to an almost unlimited extent without departing from the principles of my invention.

I claim—

1. The combination, with vertically-adjustable rollers 28 at opposite ends of the machine for supporting the tube to be operated upon and laterally-adjustable guide-rollers 36 for holding it against lateral movement, of a vertically-movable frame, a rotary cutter carried by said frame, and means, substantially as described and shown, for raising and lowering the cutter.

2. The combination, with the adjustable rollers 28, by which the tube is supported in

use, and adjustable rollers 36, by which it is held against lateral movement, of a vertically-movable frame, a rotary cutter carried by said frame, and adjustable rollers 42, placed upon 5 opposite sides of the cutter and adapted to pass between the edges of the blank, substantially as described.

3. Rollers 28 and 36, by which the tube is supported and held against lateral movement, the vertically-movable frame having an enlargement 16 and a stud 17 projecting therefrom, and the rotary cutter carried by said frame, in combination with a standard 13, having a curved slot, through which said stud 15 passes, and a nut 18, engaging said stud to lock the frame and cutter in any required position.

4. In a machine of the class described, the vertically-movable frame having an enlargement 20, a set-screw 19 in said enlargement, and a rotary cutter carried by said frame, in combination with a standard 13, having an enlargement 20, adapted to be engaged by the set-screw to limit the downward movement 25 of the frame, a spring 52, acting to draw the frame and cutter downward, a lever 22, pivoted to the frame, and a foot-lever and intermediate connections whereby the frame and cutter may be raised against the power of the 30 spring.

5. The combination, with the vertically-movable frame, the cutter, and adjustable guide-rollers 36, of supporting-rollers 28, yokes in which said rollers are mounted and 35 which are provided with shanks 30, having

pins 31, and slide 33, having oblique slots 32 engaged by said pins, so that movement of said slide will act to simultaneously raise or lower the supporting-rollers, as may be required. 40

6. The combination, with the vertically-movable frame, the cutter, and adjustable supporting-rollers 28, of guide-rollers 36, slides by which they are carried, brackets by which said slides are supported, and adjusting-screws engaging said slides, and brackets by which the guide-rollers are adjusted. 45

7. The combination, with the vertically-movable frame, the cutter, and means, substantially as described and shown, for holding and guiding the tube-blank, of rollers 42, which pass between the edges of the blank, slides 43, having arms by which said rollers are carried, a bracket having a vertical slot 44 through it and an intersecting slot 45 at 50 right angles thereto, a cross-piece 46, lying in slot 44, to the outer ends of which said slides are secured, a bolt in slot 45, engaging the cross-piece, a link pivoted to the outer end of said bolt, and a hand-lever pivoted to said 55 link, whereby the cross-piece, and with it the slides and rollers, may be raised or lowered simultaneously.

In testimony whereof I affix my signature in presence of two witnesses.

JOHN B. PERRINS.
